ATTORNEYS:

UNITED STATES PATENT OFFICE.

ALBERT H. PUTTCAMP AND LEAMON H. JUDSON, OF LOS ANGELES,
CALIFORNIA.

KEY-FASTENER.

No. 840,711.

Specification of Letters Patent.

Patented Jan. 8, 1907.

Application filed September 13, 1905. Serial No. 278,342.

To all whom it may concern:

Be it known that we, ALBERT H. PUTTCAMP and LEAMON H. JUDSON, citizens of the United States, residing at Los Angeles, in the county of Los Angeles and State of California, have invented new and useful Improvements in Key-Fasteners, of which the following is a specification.

Our invention relates to means for holding doors securely in position when such doors have been locked from one side and thereby prevent the keys from being turned to operate the lock from the opposite side of the doors by any unlawful means.

In the drawings, Figure 1 is a perspective view of the key-fasteners in place on a portion of the door. Fig. 2 is a side elevation of the key-fastener. Fig. 3 is a section on line 3 3 of Fig. 2.

In the drawings, 5 represents a portion of a door having the usual mortise-lock 6 in place therein. Secured to the inside of the door and at one side of the keyhole is a threaded stud 7, the outer end of which is bent at right angles and terminates in a head 8. Loosely mounted on the bent outer end of this stud is a key-fastener 9, which is bent to form an upper and lower member 10 and 11. Pivotaly attached to the upper member 10 of the fastener, as at 12, is a swinging catch 13, which is adapted to be thrown into or out of engagement with a shoulder 14 on the upwardly-turned spring-catch 15 formed on the outer end of the lower member 11. The lower member is provided with a key-engaging pin 16, which is adapted to enter the aperture 17 in the key-head and prevent the key from slipping on being pushed out of the fastener. Both members have apertures 18 at their outer end, which engage the threaded stud 7.

The outer bent end of the stud may be

threaded to receive a nut, (not shown,) so that the fastener may be put on or removed without removing the stud from the door. 45

It will be seen that the device described is simple in construction, has but few parts, easily adjusted, and constitutes an effectual safeguard against unauthorized unlocking of the door. 50

Having described our invention, what we claim as new, and desire to secure by Letters Patent, is—

1. The improved key-fastener provided with means for attachment to a door; a plate 55 bent to form an upper and lower member loosely secured to said attaching means; a hinged catch pivotally secured to said upper member, the lower member being turned upwardly at its outer end to form a spring- 60 catch having a shoulder adapted to receive the swinging catch of the upper member; and a key-engaging pin secured to said lower member.

2. In a device of the character herein described comprising a threaded stud bent at right angles at its outer end and having a head, adapted to be secured to a door; a fastener loosely mounted on said stud, said fastener bent to form an upper and lower member, 70 the upper member provided with a hinged catch adapted to be pressed into engagement with a shoulder on the spring-catch formed on the outer end of the lower member; a key-engaging pin secured to said 75 lower member.

In witness that we claim the foregoing we have hereunto subscribed our names this 29th day of August, 1905.

ALBERT H. PUTTCAMP.
LEAMON H. JUDSON.
